UNITED STATES PATENT OFFICE.

WILLIAM A. ST. GERMAIN, OF GREENVILLE, MAINE.

TWO-CYCLE ENGINE.

No. 874,634.

Specification of Letters Patent.

Patented Dec. 24, 1907.

Application filed May 24, 1906. Serial No. 318,570.

To all whom it may concern:

Be it known that I, WILLIAM A. ST. GERMAIN, a citizen of the United States, residing at Greenville, in the county of Piscataquis and State of Maine, have invented a new and useful Two-Cycle Engine, of which the following is a specification.

This invention relates to two cycle internal combustion engines, and has for its principal object to provide a double piston two cycle engine so designed as to secure two working strokes for each revolution of the crank shaft.

A further object of the invention is to provide a double piston two cycle engine in which the compression chambers are arranged for connection with a single source of supply, such for instance as a carburetor, and further to provide for the more positive closing and seating of the valves which control communication between the source of supply and the compression chambers.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a sectional elevation of a two cycle engine constructed in accordance with the invention. Fig. 2 is a vertical sectional view of the same taken on the plane at right angles to the section of Fig. 1. Fig. 3 is a plan view of the engine.

Similar numerals of reference are employed to indicate corresponding parts throughout the several figures of the drawings.

The upper and lower cylinders 10 and 11 are preferably cast integral with the upper half of the crank casing 12, this latter being preferably formed in two sections and having bearings for the reception of the crank shaft 13. The crank casing is closed and forms a chamber in which the successive charges to be introduced into the lower cylinder are compressed.

Arranged within the upper and lower cylinders are pistons 16 and 17, respectively, said pistons being rigidly connected to each

other by a rod 18, and the lower piston being connected to the crank shaft by a rod 19. The piston rod 18 is arranged to travel through stuffing boxes 20 formed at the adjacent end of the two cylinders, said stuffing boxes being preferably arranged to contain metallic rings 21 that are held in place by gland nuts 22, although any other suitable form of box may be employed for the purpose of preventing leakage between the explosion chambers and the two cylinders. The cylinder heads are spaced from each other by a water chamber 23, in communication with the outer water jacket 24 that surrounds the explosion chambers of both cylinders, any suitable connection being employed to promote the circulation of water through the jacket.

The main casting is preferably so formed as to include a portion of a compression chamber 25 that is in free communication with the upper open end of the cylinder 10, and the top of this compression chamber is formed of a cap or cover 26 which may be held in place by a suitable bolt 27, entering a boss 27' on the upper end of the cylinder, and such other connections as may be necessary. The chamber 25 communicates with the upper end of the cylinder 10 through the spaces 26' on opposite sides of the boss 27', Fig. 2. The lower compression chamber communicates with the upper end of the cylinder 11 through a port 28 which is opened by the piston 17, as the latter completes its down or in stroke, and the compression chamber 25 is placed in communication with the lower end of the cylinder 10 by a port 29 that is opened by piston 16, as the latter completes its upward or out stroke, and the pistons are provided with the usual deflecting plates 30 for the purpose of directing the fresh charges toward the heads of the explosion chambers.

Leading from the two cylinders at points diametrically opposite the inlet ports 28 and 29 are exhaust ports 33 and 14 which communicate with an exhaust pipe 35, and said exhaust pipe may be reversed in order to direct the exhausted gases upward instead of downward, as shown in Fig. 1.

At one side of the cylinders is arranged a valve casing 36 that preferably is cylindrical in form and is divided by a pair of partitions 37 and 38 into three chambers, the central chamber being provided with an inlet connection 39 that leads from a carburetor

or other suitable source of supply. The upper chamber is connected by a pipe 40 to the compression chamber 25 of the upper cylinder, while the lower chamber of the valve casing is connected by a pipe 41 to the crank casing or compression chamber of the lower cylinder. The two ported partitions 37 and 38 are provided with oppositely facing valve seats 46' and 47', and have guides 45' for the reception of a slideable valve stem 45 having two oppositely facing valves 46 and 47, one of which is always closed, while the other is open.

In the operation of the engine as thus far described, it will be seen that when the parts are in the positions shown in Fig. 1, the upper piston 16 has completed a working stroke, and the products of combustion are escaping through the port 34, while the fresh charge is entering the cylinder through the port 29, and at this time the valve 46 is held closed by the pressure of gas or explosive mixture in said chamber 25. The lower piston 17 has just completed an up or working compression stroke, and the compressed charge in the upper portion of the cylinder is about being ignited. This upward stroke of the lower piston has created a partial vacuum within the lower compression chamber, resulting in the opening of the valve 47, so that a fresh charge may flow from the carbureter into the crank casing. When the charge is ignited in the upper end of the cylinder 11, the piston 17 will be forced down and will compress the charge previously drawn into the crank casing, and the increase in pressure which results in the lower portion of the valve casing 36 tends to move the valve 47 to closed position. At the same time downward movement of the piston 16 is creating a partial vacuum in the chamber 25, so that there is a tendency to lift the valve 47, and these forces, operating simultaneously on the valves, will move valve 47 positively to closed position and will open the valve 46, so that a fresh charge may flow from the carbureter into the chamber 25 as the down stroke continues. When the piston 17 near the limit of its down stroke, the escape port 33 is opened and the products of combustion will start to escape from the cylinder 11, and on slight further movement, the inlet port 28 will be opened and the fresh charge of gas entering the upper end of the cylinder will be directed by the deflector 30 toward the head of the explosion chamber and will act to sweep out all or the greater part of the exhaust gases through the port 33, so that when the up stroke of the piston 17 commences, and the ports are closed, the cylinder will contain nothing but the fresh charge of gas. When the down stroke of the piston is completed, the charge in the upper chamber 10 is compressed and is ignited, so that each stroke

of the engine is a working stroke, and two working strokes will occur for each revolution of the crank shaft.

The working charges may be ignited in any suitable manner, and in Fig. 2 jump spark 70 plugs 50 have been shown in recesses near the heads of the explosion chambers. These are suitably connected to an adjustable commutator 51 that is disposed at the upper end of a vertical shaft 52 connected 75 by a skew gearing 53 to the main shaft.

It will be seen that no valves are employed in this engine, with the exception of those between the compression chambers and the carbureter or other source of supply, 80 and that an engine of practically double the horse power of a single acting two cycle engine is secured, and the weight is but slightly greater than that of a single acting engine.

I claim:—

1. In an internal combustion engine, a pair of cylinders arranged head to head and in alignment with each other, pistons in said cylinders, a piston rod extending through the head cylinder and to which both pistons 90 are secured, a crank shaft connected to one of the pistons, upper and lower compression chambers connected to the open ends of the cylinders, inlet ports leading from the compression chambers through the walls of the 95 cylinders, exhaust ports leading from the cylinders and arranged to be uncovered by the pistons at the outer limits of their strokes, all of said ports being controlled by the pistons, a valve chamber intermediate 100 the compression chambers and having a fluid inlet, and valves arranged in said valve chamber and controlling communication between the latter and the compression chambers.

2. In an internal combustion engine, a pair of cylinders arranged tandem and having their explosion chambers adjacent to each other, a crank casing in communication with the open end of the inner cylinder, and forming a compression chamber, a second compression chamber in free communication with the open end of the other cylinder, piston controlled inlet ports leading from the compression chambers to the respective cylinders, exhaust ports leading from the cylinders, a valve casing in communication with a source of supply and with the two compression chambers, and connected and simultaneously acting valves arranged in said casing for alternately placing the chambers in communication with the source of supply.

3. In an internal combustion engine, a pair of cylinders arranged tandem, compression chambers in communication with the open ends of the cylinders, ports leading from the compression chambers through the walls of said cylinders, exhaust ports also leading through the walls of the cylinders, a pair of connected pistons disposed in said 130

cylinders and controlling the ports, a valve casing in communication with a source of supply, and with the two compression chambers, and a pair of valves arranged in said 5 valve chamber, said valves being simultaneously acted upon by the pressure from one chamber and the suction or partial vacuum formed in the other chamber, whereby the valves are moved to alternately place said 10 chambers in communication with the source of supply.

4. In an internal combustion engine, a pair of cylinders arranged tandem, having their explosion chambers adjacent to each 15 other, the heads of the explosion chambers being separated by a water space, stuffing boxes in said heads, a piston rod extending through the stuffing boxes, pistons secured to the rod and arranged within the cylinders, 20 upper and lower compression chambers in communication with the open ends of the cylinders, piston controlled inlet ports leading from said chambers to the cylinders, piston controlled exhaust ports leading from 25 the cylinders, a valve casing, having ported partitions and provided with valve seats, said casing being in communication with a source of supply and with the upper and

lower compression chambers, and a pair of connected valves adapted to the seats, said 30 valves being exposed to the pressure of one chamber and the suction or partial vacuum simultaneously formed in the other chamber.

5. In an internal combustion engine, the combination with a pair of cylinders, pistons 35 therein, a pair of chambers connected to said cylinders, the pistons operating to simultaneously produce a partial vacuum in one of the chambers, and a compression in the other chamber, a branched supply conduit 40 connected with the chambers, a valve casing at the point of branching of the conduit, valves in the casing for controlling the supply through each branch of the conduit, and means for connecting the valves to move simultaneously by the combined effect of the 45 vacuum in one chamber and the compression in the other.

In testimony that I claim the foregoing as my own, I have hereto affixed my signature 50 in the presence of two witnesses.

WILLIAM A. ST. GERMAIN.
